ABSTRACT OF THE DISCLOSURE

A church kneeler or like article of furniture adapted to swing from a substantially horizontal supporting position to a generally out-of-the-way vertical position, which is especially constructed for attachment to pews or other furniture having relatively narrow legs. The kneeler is held through a plurality of support plates and associated pivotal arms and each assembly contains a stop means for limiting rotation of the pivot, and each stop means is formed with one part on the support plate and another part on the pivotal arm and rotatable therewith so that contact of the two elements will provide the limit position. The stop means are also formed in a general vertical alignment with and close to the pivot so as to present a pleasing appearance when mounted on a relatively narrow leg. The device is particularly adapted to church kneelers and other devices, which are provided with damping means for damping the movement of the device as it approaches the limit of travel in both directions.

BACKGROUND OF THE INVENTION

The present invention relates to improvements in a swingable support device, and more particularly to a swingable device adapted to swing between two terminal positions such as a church kneeler.

It is well known to provide articles of furniture such as church kneelers where a support surface is used temporarily in one position and then moved pivotally to an out-of-the-way or storage position when not in use. Considerable effort has been expended in developing devices of this character, which operates smoothly and swing in dampened fashion toward each of the terminal positions. Examples of such devices are to be found in my prior United States Patent Nos. 3,107,122, 3,190,695 and 3,273,938. These patented and other kneeler constructions have been developed so as to be removable from the pews and installable on old pews. The device is generally mounted through a support plate which is held by screws or the like in the desired location on the face of the pew leg so as to orient the kneeler in the proper operative position. While these structures have been eminently satisfactory, they have been designed particularly for use on pew legs that have relatively large surfaces and on which large support plates can be mounted in an inclined position. In addition, means for limiting the upper position have been provided at a distance remote from the pivot and considerably off-set from the vertical thereto. However, it is sometimes desirable to mount kneelers on pews having relatively narrow legs such as metal legs and to equip such pews with improved kneelers. It is also desirable to provide leeway in the design of new pews, so as to effect a saving in wood and present a more "modern" or different appearance.

BRIEF SUMMARY OF THE INVENTION

From the foregoing discussion, it is seen that a primary object of the present invention is the provision of a church kneeler suitable for simple and effective mounting on relatively narrow pew legs, so as to present a comparatively narrow vertical support structure, while at the same time providing satisfactory structures to insure terminal posi-

2

tions, one at a horizontal position and the other at a slightly forwardly inclined position.

Another object of the invention is the provision of a church kneeler or similar swingable support device of the character described in which a relatively narrow and strong mounting can be effected in combination with means for dampening the movement of the swinging device toward each terminal position.

A further object of the invention is the provision of a swingable support device of the character described, which is economic in construction, and reliable in operation.

Further objects and advantages of the invention will appear as the specification proceeds, and the new and novel features of the swingable support device will be fully defined in the claims attached hereto.

In its broad form, the invention embraces the use of a modified support plate which is formed to fit a relatively narrow pew leg in vertical orientation, while at the same time providing its component of the stop means in said vertical position in cooperation with a corresponding component of the stop means carried on the swingable structure. In addition, this support plate is preferably formed to carry a suitable auxiliary damping means in the proper orientation, and yet retain its substantially vertical configuration. More particularly, the modified support plate provides for a change of location of the elements of the stop means so as to achieve the improved function. Where dampening arms are provided, the modified support plate also provides a change in location of the pivot point of the dampening arms so as to present a pleasing appearance and retain the full strength. Accordingly, the improvement described herein is achieved without in any way detracting from the operation and normal function of the desired device.

BRIEF DESCRIPTION OF THE DRAWING

The preferred form of the invention is illustrated in the accompanying drawing, forming part of this application, in which:

FIGURE 1 shows a perspective rear view of a church bench having a kneeler attached thereto in accordance with the invention, the kneeler being shown in an upright position on the left side and in a horizontal position on the right side of the figure;

FIGURE 2, an enlarged, vertical section taken substantially on the plane of line 2—2 of FIGURE 1; and

FIGURE 3, an end elevational view of the portion of the device shown in FIGURE 2 substantially as seen in the plane indicated by the line 3—3 thereof.

While only the preferred form of the invention is shown, it should be understood that various changes or modifications may be made within the scope of the claims hereto attached, without departing from the spirit of the invention.

DETAILED DESCRIPTION OF THE INVENTION

Referring to the drawing in detail, FIGURE 1 illustrates the general arrangement in rear view of a church bench 11 having two aligned sections 12 and 13, with each of said sections 12 and 13 constructed to carry a kneeler 14. The church bench 11, here shown, is illustrated with six relatively narrow legs 16, and the two kneelers 14 are supported between adjacent pairs of legs 16 thereof.

As here shown, the kneelers each comprise an elongated cushion 17 extending through the full length of each section, two kneeler legs 18 for each section adapted for supporting the cushion horizontally behind the bench, said kneeler legs providing support at an elevation suitable for kneeling, a pair of support plates adapted to fit on each of an adjacent pair of supporting legs 16 of the bench, and a pair of arms 21 appropriately fastened to the cushion.

ion 17 and pivotally mounted to the support plates 19 through appropriate connecting hardware such as the brace 22. While the arms and braces are shown as separate elements, it will be appreciated that they may be integrally connected in a single part, but of similar configuration to that shown and described below.

In the embodiment herein illustrated, the support plate 19 is in the form of an elongated plate, having a pivot pin 23 integrally associated therewith and extending into a hub 24 of the brace 22 to accommodate relatively pivotal movement. The brace also contains a post 26 located below the pivot point, with the post 26 having a rubber collar 27 serving as a shock absorber. The support plate 19 is secured to a leg 16 through screws 28 an any other suitable fastening means, and it will be seen in FIGURE 2 that the support plate fits generally along the vertical of the leg so as to blend therewith while providing a strong construction.

The brace 22 is secured to arm 21 of the kneeler through a pair of bolts 29 or like fasteners, one of which is secured at the pivot position to the main hub of the brace, and the other is secured to an extension 31 thereof. The hub portion 24 of the brace 22 also contains a projection 32 equipped with a suitable cushion 33 made of rubber or the like, with the projection serving as a stop.

The projection 32 and the post 26 cooperate together to form stop means limiting the upward and forward travel of the kneeler 17 so as to limit its forward travel. In this way, the stop means also holds the kneeler in the upper position because of a slight forward incline of the kneeler, or because of urging by the damping means, or both.

It will be observed, that the stop means provides and positively prevents forward movement of the kneeler, and it is formed to act substantially alone. Accordingly, it is important to provide rather strong stop means which are capable of holding rather strong forces at the end of the lever arm involved. For this reason, it is preferred to use steel or the like for the posts and projections or equivalent structures providing the contacting surfaces at the limit position. Hard rubber cushions are utilized to minimize noise and wear and the like. By utilizing relatively strong parts, of suitable dimensions, it is found that absolutely reliable stop means is provided in spite of the short lever arm and that the device is positively reliable in maintaining the top terminal position.

The preferred embodiment here shown also includes damping means 34 which is in the form of a special cylinder and piston structure connected at one end to an ear 36 of the brace and at the other end to the arm 21 of the kneeler near the end remote from the pivot. This damping means is equipped with a spring and hydraulic system and is constructed to assist in driving the kneeler toward each terminal position and maintaining it there, while at the same time slowing down the movement toward the terminal position. In this way, easy operation of the kneeler is provided while slaming and the accompanying noises caused thereby is prevented. Since the damping means is a rather special structure, it is important that it be protected against over movement of the kneeler, and the stop means herein described also serves to protect the damping means as well as positively fix the terminal position.

In the device here shown, the kneeler is also equipped with a spring between the hub 24 of the brace 22 and pivot pin 23 of support plate 19 in order to assist in overcoming the gravitational force and allowing easier lifting of the kneeler from the horizontal position. The particular hub structure and the damping means herein utilized and illustrated is the same as that shown and described in my United States Patent No. 3,190,695, and a more detailed description of these parts may be found by referring to that patent. However, it will be appreciated that the special construction herein shown is suitable for

mounting various different kneelers on narrow pew legs, and the showing of the embodiment in the drawing is being made only for the purpose of illustrating the preferred form of the invention. However, it will be appreciated that the invention provides special utility in combination with these known structures when used with relatively narrow pew legs or the like.

It will also be appreciated that while the invention has been described in detail for church kneelers, that it may be utilized for any item of furniture such as a tray where similar movement from a horizontal to a relatively vertical position is desirable, and where the moving item is to be attached to relatively narrow supports as herein illustrated. In such cases, a second terminal stop means may be needed for the horizontal limit, which limit is provided in church pews by the contact of the kneeler legs and the floor.

From the foregoing description, it is seen that I have provided an improved swingable support device suitable for attachment to relatively narrow legs, yet which provides for limits to terminal positions in a reliable manner utilizing a minimum of parts.

I claim:

1. A kneeler pivotally mounted through a plurality of arms for swinging movement between two end positions including movement from a normally substantially horizontal position through a slightly obtuse angle to a position slightly inclined from the vertical, comprising an elongated support plate formed to fit on a surface of a relatively narrow pew leg, a brace carried on an arm of the kneeler, pivot mounting means on said support plate formed to fit the brace for pivotally mounting the kneeler on said support plate, and stop means on said support plate and on the brace formed for limiting the degree of pivot of the kneeler; said stop means comprising a post carried on the support plate below the pivot position, and a lug on the brace formed to rotate with the brace and associated kneeler arm, with the lug and post oriented so that the lug moves against the post at the desired terminal position.
2. The kneeler defined in claim 1, in which damping means are provided for controlling the movement of the kneeler toward each terminal position in a controlled slow fashion.
3. The kneeler defined in claim 1, in which the post and lug each have a cushion on the surface area of contact thereof.

4. In an article of furniture having a pair of relatively vertical members suitable for providing a support, in combination, a swingable support device pivotally mounted on said vertical members for swinging movement between a substantially horizontal position and a higher position close to the vertical, said support device comprising

- a member providing a support surface,
- a pair of arms carried on said member and extending from one side thereof, each of said arms including a brace at the end opposite the member,
- a pair of elongated support plates mounted in opposed positions on the pair of vertical members, each of said support plates and brace being pivotally connected for providing the pivotal mounting of the support device, and
- a stop means on each associated support plate and brace for limiting the pivotal movement of the support device in at least one direction;
- said stop means, comprising
- a first element carried on the brace of rotational movement as the brace is pivoted and a second element carried on the support plate in a fixed position, said first and second elements having surfaces adapted to contact at the desired terminal position.

3,494,666

5

5. The article defined in claim 4, in which the first element and second element each have a cushion at the surface adapted to make contact.

6. The article defined in claim 4, in which the first element is a post carried on the support plate below the pivot position, and the second element is a lug. 5
